UNITED STATES PATENT OFFICE.

WILLIAM L. STARR, OF AMERICUS, GEORGIA.

ELECTRIC-SWITCH LOCK.

1,317,053.

Specification of Letters Patent. Patented Sept. 23, 1919.

Application filed August 8, 1918. Serial No. 248,957.

To all whom it may concern:

Be it known that I, WILLIAM L. STARR, a citizen of the United States, residing at Americus, in the county of Sumter, State 5 of Georgia, have invented a new and useful Electric-Switch Lock; and I do hereby declare the following to be a full, clear, and exact description of the invention, such as will enable others skilled in the art to which 10 it appertains to make and use the same.

The present invention relates to a lock for electric switches, and has for its object to provide a device of this character which embodies novel features of construction 15 whereby a knife blade switch such as are commonly employed in stores, dwellings and other buildings for controlling electric lighting and other circuits can be effectively locked in such a manner as to prevent tampering therewith by children or unauthorized persons.

Further objects of the invention are to provide a device of this character which can be readily applied to an ordinary knife 25 blade switch and used in connection therewith, which is adjustable for use under different conditions, and which can be quickly manipulated to lock or release the switch.

With these and other objects in view, the 30 invention consists in certain novel combinations and arrangements of the parts as will more fully appear as the description proceeds, the novel features thereof being pointed out in the appended claims.

For a full understanding of the invention, 35 reference is to be had to the following description and accompanying drawings, in which:—

Figure 1 is a top plan view of a knife 40 blade switch provided with a locking device constructed in accordance with the invention, the swinging member of the switch being shown as swung into position to close the circuit.

Fig. 2 is a side elevation of the same with the swinging member swung into and locked in an open position.

Fig. 3 is a longitudinal sectional view 50 through the switch and locking device, the knife blades being shown as locked in an open position.

Corresponding and like parts are referred to in the following description and indi-

cated in all the views of the drawings by the same reference characters. 55

For the purpose of illustration the locking device is shown as applied to a conventional knife blade switch which includes an insulating base 1, the spring contact members 2, and the knife blades 3 which are pivoted upon the posts 4^a and adapted to be swung into and out of engagement with the spring contact members 2. At their swinging ends the knife blades 3 are connected by a cross bar 4 which is provided with the 60 usual handle 5. All of the above is of the usual and conventional construction.

The locking device includes a bar 6 which projects from one end of the switch base 1 and is rigidly secured to the base by suitable means such as the screws 7. A slide 8 is mounted upon the locking bar 6 and carries a standard 9 upon the upper end of which a locking arm 10 is pivoted at 11. A second slide 12 is also mounted upon the 70 locking bar and provided with a standard 13 which is looped to provide a keeper adapted to receive the free end of the arm 10. It will be obvious that when the swinging member of the switch is swung rearwardly into an open position and the cross bar 4 thereof brought between the standards 9 and 13, with the arm 10 swung over the cross bar and engaged by the standard 80 13, it will be impossible to swing the knife 85 blades back into position to close the electric circuit.

A tang 14 is carried by the slide 8 and extends along the top of the bar 6, passing through the slide 12 which is also provided with a short tang 15. These tangs 14 and 90 15, as well as the locking bar 6 are provided with perforations 16, and when the device is in operative position the opening 16 of the tang 15 is brought into registry with one of the openings 16 in the tang 14, and also one of the openings 16 in the bar 6, and the shackle of a conventional padlock 17 inserted through the registering openings. The parts are thus securely locked in position so that it is impossible for any children or unauthorized persons to tamper with the switch. However, when it is desired to close the switch, it is merely necessary to remove the padlock 17 and move either the slide 12 95 or the slide 8 a sufficient amount to release 100 105

the arm 10, whereupon the swinging member of the switch can be swung forwardly and the knife blades brought into engagement with the spring contacts 2.

5 Having thus described the invention, what I claim as new and desire to secure by Letters Patent, is:—

10 1. The combination with a knife blade switch, of a bar projecting from the switch base, a pair of slides adjustable upon the bar, standards projecting from the slides, a pivoted locking arm carried by one standard and adapted to extend over the swinging member of the switch and engage the 15 other standard, and means for locking the standards in an adjusted position upon the bar.

20 2. The combination with a knife blade switch, of a bar projecting from the switch base, a pair of slides adjustable upon the bar, tangs projecting from the slides and overlapping each other and the bar, means for locking the tangs to the bar to hold the slides in adjusted positions, a standard projecting from one slide, a pivoted locking 25

arm carried by the standard and a looped standard projecting from the other slide for receiving the end of the locking arm.

3. The combination with a knife blade switch, of a bar projecting from the switch 30 base and provided with a series of perforations, a pair of slides mounted upon the bar, tangs projecting from the slides and overlapping each other and the bar, said tangs being provided with perforations of 35 which selected ones can be brought into registry with one of the perforations of the bar, a lock for engaging the registering perforations to lock the slides in position upon the bar, a standard upon one of the slides, 40 a swinging locking arm carried by the standard, and a looped standard carried by the other slide for engaging the locking arm.

45 In testimony whereof I have signed my name to this specification in the presence of two subscribing witnesses.

WILLIAM L. STARR.
